UNITED STATES PATENT OFFICE

2,538,564

BREAD-WRAPPING MACHINE

Thormod Jensen, Laurelton, N. Y., and Frederick A. Drury, Jersey City, N. J., assignors to American Machine & Foundry Company, a corporation of New Jersey

Application June 27, 1946, Serial No. 679,736

14 Claims. (Cl. 93—2)

1 This invention relates to wrapping machines suitable for wrapping an article, such as bread, and more particularly to providing mechanism for applying a tear strip and forming a tear tab on the bread wrapper to facilitate the removal of the wrapper from the article; and also relates to an improved method of incorporating a tear strip with a wrapper.

Heretofore, various devices have been designed for applying tear strips to wrapped articles such as cigarettes and chewing gum packages. In packages of this type, the tear tab is usually formed adjacent the edge of the articles and the projection of the tab from the article has been the natural extension of the tear tab. In the field of bread wrapping, however, no such device is available.

One of the obstacles in providing a tear strip to a bread loaf is the fact that the seam where the tear tab is formed is on the bottom central portion of a bread loaf and not always adjacent the edge of the loaf. As a result, the tab would have a tendency to adhere closely to the wrapper making it difficult to grip in this form and thus be of little, if any, assistance to the consumer.

It is, therefore, an object of this invention to provide a tear tab and a tear strip which can be formed and used on an article such as a bread loaf which is so constructed and arranged that a customer can easily find and grip the tab to remove the wrapper.

Another object of the present invention is to provide, at a minimum cost, mechanism which can be readily incorporated with most bread wrapping machines now on the market and which can apply tear strips to various types of wrapping material.

Another object is to provide a positive means for engaging a tear tab and bending it in such a way as to cause it to project from the wrapped article.

A further object is to provide a novel type of cutter which will be used in conjunction with the tear strip to facilitate the formation of a tab.

A further object is to provide a method of applying tear strip material to bread wrappers to form wrapped loaves of bread having tear tabs.

Other objects and features of the invention will appear as the particular physical embodiment selected to illustrate the invention progresses. In the accompanying drawings which form a part of this specification, like characters of reference have been applied to corresponding parts throughout the several views which make up the drawings.

Figure 1 is a schematic side elevation illustrating the tear strip and web feeding mechanism of the wrapping device;

Figure 2 is a detailed plan view of the tear strip

2 applying mechanism taken on line 2—2 of Figure 1;

Figure 3 is a partial plan view of the loaf runway illustrating the tear tab bending mechanism as seen from line 3—3 of Figure 1;

Figure 4 is a partial plan view of the severing and slitting knives;

Figure 5 is a sectional end elevation of the same taken on line 5—5 of Figure 4;

Figure 6 is a detail view showing the severed end of the wrapper web and affixed tear strip material, and the longitudinal slits on each side of the tear strip;

Figure 7 is a detail view showing how a rotating brush engages and forms the downwardly extending tear tab;

Figure 8 is a perspective view of the wrapped article illustrating the tear tab;

Figure 9 is a plan view of a modified method of forming the tear tab; and

Figure 10 is a side elevation of same.

A web W (Fig. 1), consisting of suitable heat-sealing bread wrapping material such as cellophane, is fed from a reel R between rollers 20 and 22. The tear strip T, consisting of suitable material such as cellophane, is fed from a spool S over a guide roller 24, then under a stationary stud 26, and over a roller 28. The roller 28 applies a solvent to the tear strip causing the surface of the strip to become soft and tacky which facilitates its being affixed to the web W.

The tear strip then passes under roller 20, around a guide roller 30, and then between rollers 20 and 22 to be affixed to the wrapper web W.

35 The combined wrapper web and tear strip WT pass between roller 22 and an ironer block 32 having a heater element 34 to dry the tacky cellulose coating and affix the strip to the wrapper web so that the tear strip, as it is fed through the machine, will not become displaced with respect to the wrapper. If the wrapper web W consists of wax paper, a suitable heating element may be employed to preheat the wrapper web before the tear strip is affixed thereto. When

40 the wrapper web W consists of wax paper, the tear strip may be affixed to the wrapper web by heating elements and the use of solvents on the tear strip will not be necessary. The web WT is then led around a suitably driven feed roller 35 and travels upwardly around feed roller 38, downwardly around a floating roller 40 and continues upwardly again passing over a roller 42 on to a guide shelf 44 of the wrapping machine. The floating roller 40 is guided in its vertical movement by the guide-way 46 which forms a part of the machine.

To facilitate the installation and removal of the strip applying device, shown in Figs. 1 and 2, the frame 48 is provided with open end slots

60

50 which are adapted to rest on bars 52 mounted in the bread wrapping machine.

Collars 53 (Fig. 2), having set screw 55, are provided for positioning the device longitudinally so that the strip can be applied to any desired portion of the wrapper web W. The frame 48 is equipped with shafts 54 and 56; the former shaft carries the guide roller 24 and the latter shaft supports the guide roller 30 and an arm 58. Arm 58 supports a stud 59 on which is mounted the strip applying roller 20. One end of arm 58 carries an ironer block 32 and the other end carries a stud 60. One end of a spring 62 is connected to the stud 60 and the other end is connected to stud 64 mounted in frame 48. The spring 62 acts to hold the roller 20 and ironer block 32 in engagement with roller 22. Frame 48 is provided with a track 66 adapted to receive the base 68 of the solvent receptacle 70 and a locking screw 72 provides means for securing the receptacle in place. The solvent applying roller 28 is mounted on a shaft 74 turning on trunnions 76 carried by the receptacle 70.

The articles to be wrapped are intermittently propelled over a runway plate 78 (Fig. 1) by suitable means not shown. A reciprocating pusher 80 of the wrapping machine conveys the article A from the runway plate 78 on to the lifter table 82 when the table is in its down position as shown in dotted lines in Fig. 1. On approaching lifter table 82, the article encounters the hanging end of the web WT, shown in dotted lines, and moves the same on to the table whereby the web partly encircles the article. When the article enters on the table 82, the web becomes clamped in a manner similar to that shown in U. S. Patent No. 2,385,706 issued to T. Jensen, at which time an arm 84 is actuated by suitable means (not shown) and lifted from engagement with the wrapper web resting on the shelf 44, thus permitting the article to draw material from the reels R and S.

When the article is in position on table 82, the pusher 80 retreats to its starting position in readiness to engage the succeeding article. A 45 pair of conventional or other suitable tucker plates (not shown), carried by the lifter table 82, engage the extending side webs of the wrapper and fold the same against the article as the same enters on to the table. With the article thus positioned, the table is swung to its up position. On approaching this latter station, suitable folder plates (not shown) engage the extending top webs of the wrapper and fold them down against the article. If desired, U. S. Patent No. 2,391,316, issued to T. Jensen on December 18, 1945, may be referred to for a more detailed showing of the operation of the lifter table and folding mechanism.

A lap roller 86, carried by arms 88, now acts on the wrapper web and draws additional material from the reels R and S to provide sufficient web for the initial folding of the succeeding article to be wrapped. With a sufficient length of web delivered, suitable mechanism such as the arm 84 descends and clamps the web that is resting on shelf 44. At this time, a knife 90, having a scalloped edge (Figs. 1, 4 and 5) of conventional design, is actuated in a manner similar to that shown in U. S. Patent No. 2,385,706 and patent issued to F. R. Schmitt No. 1,851,295, and severs the web WT. The free end of web WT then falls to a position shown in dotted lines in Fig. 1 and will be engaged by the next succeeding article advanced by the pusher 80 in the manner just described.

The knife 90 has attached to its upper surface a tear tab forming knife 92 (Figs. 1, 4 and 5). Two spaced extending ears 94 are formed on the slitting knife 92. The knife 92 is secured in position by means of two screws 98, extending through two elongated slots 96, which permits the knife to be adjustably moved with respect to knife 90. As the cutter 90 is advanced to sever the web, the ears 94 first engage and pierce the web to form two elongated slits on each side of the tear strip. The continued advancement of the cutter 90 then brings the serrated cutting knife 90 into engagement with the web WT and severs the same.

15 With web WT severed, pushers 102 depending from the lower run of conveyor chains 104 engage and propel the article A from the lifter table 82 into a channel formed by end folder plates 106 and 108 and a bottom folding and sealing table 110. In entering said channel the hanging end of the wrapper web is folded by the leading edge of plate 110 and thereby completes the bottom lap of the article. The extending side webs of the wrapper are folded against the ends of the article by the leading edge 112 of each folder plate 106. As the article is being conveyed rearward in the machine, the extending bottom flaps of the wrapper web enter into the fold-way 114 of the folder plates 106 and 108, whereby the flaps will be folded upward against the article to complete the wrapping of the same. Each of the folder plates 106 and 108 is equipped with suitable heaters 116 and 118 respectively, the same being provided to start the initial heat-sealing of the end flaps of the wrapper.

20 The bottom sealing table in the present application consists of spaced plates 110 (Fig. 3) thus forming a longitudinal slot 120 so positioned that the tear strip zone Z will not be heat-sealed in its travel over said table. Each plate 110 is equipped with a suitable heater 122 provided to heat-seal the bottom flap of the wrapper, with the exception of the portion adjacent the tear strip zone. In traveling rearward, the article emerges from the folder channel and enters into the sealing chamber consisting of the sealer table 110 and spaced plates 124, the latter being provided with suitable heater members 126 to heat-seal the end flaps of the wrapper.

25 In entering the sealing chamber above mentioned, the articles pass over a rotating brush 128 (Fig. 1) which is located in the slot portion 120 of sealer table 110. The brush 128 is so mounted that it extends upwardly to engage the bottom of the wrapped article and thereby the slotted portion N of the web is brushed downwardly out of engagement with the article to bend the tear tab P (Fig. 7) so that it will project and be easily gripped by the consumer. Since the tear strip zone Z does not have any heating element coming in contact with the slotted portion of the wrapper, the formation of the tear tab P by the brush 128 is facilitated. The spaced slits N (Fig. 6) also facilitates turning back the wrapper to form a tear tab. The longitudinal slits N offer the advantage of producing a comparatively large tab which can be easily seen and gripped by the consumer.

30 The rotating brush 128 (Figs. 1 and 3) is adjustably mounted on a shaft 130 turning in bearing brackets 132 secured to table 110. A pulley 134, fastened on shaft 130, is driven by a belt 136 from a pulley not shown on the drive shaft of the machine. The peripheral speed of the brush is such that it is greater than the forward move-

ment of each article in order that the proper tab formation P can be effected.

The wrapped article, after passing the tab forming brush 128, passes over a series of independently acting sealing fingers 138 adapted to seal the bottom flap of the wrapper. Said fingers are provided to engage the irregular or hollow bottom contour of articles such as loaves of broad and thus assure a perfectly sealed bottom flap. The sealer fingers 138 are omitted at the tear strip zone so that the same will not be heat-sealed. A stationary shaft 140, which supports the sealer fingers, is provided with a spacer 142 (Fig. 9) so positioned that it spaces the sealer fingers 138 from the tear strip zone. Each finger 138 has a depending arm 144 (Fig. 1) supporting one end of a tension spring 146 connecting to a spring post 148 supported by the take-off table 150 of the machine. The plurality of sealer fingers are arranged in the space between table 110 and table 150 and the springs 146 normally tend to hold the fingers in their up position in the path of the articles. A strip heater 152 serves to heat the fingers 138 in order that they can seal the bottom flap of the wrapper.

In twin-pack or pantry loaf forming machines, it is advantageous to position the tear strip in the center of the package longitudinally as shown in Fig. 3 in order that the wrapper can be opened to expose the twin-pack loaves or, in the case of pantry loaves, the two different types of bread enveloped will be exposed. The pantry loaf is formed by combining two half sections of bread to form a complete loaf. Thus, when the wrapper is parted in the center, the contents will be separated permitting the same to be used at the discretion of the consumer.

When a tear strip web T consists of heat-sealing material, the solvent receptacle 70 (Fig. 1) may be removed from its holder 48 or moved sufficiently so that roller 28 will not contact with passing web T. It will be understood that the strip will be threaded around its several guide rollers and feed roller as heretofore described. The strip T becomes affixed to the wrapper web W when passing between the roller 22 and the ironer block 32.

If tear strip T consists of paper or material other than heat-sealing material, receptacle 70 may be supplied with an adhesive so that roller 28 will apply a coating of adhesive to strip T. In such an instance, the tear strip T, after being guided about the various rollers shown in Fig. 1, will be fixed to the wrapper web W as it passes between roller 22 and the ironer block 32. The ironer block 32 serves to dry the adhesive and thus avoids smudging of the different part of the machine that the strip passes over.

The wrapper web may also be fed without a tear strip band. In this case, the longitudinal slits N will serve to form a tear tab P when engaged by the revolving brush 128 heretofore described. By pulling the formed tear tab just mentioned, the wrapper around the article will be parted to expose the enclosed contents.

In Figures 9 and 10, a modified form of the invention is shown for forming the tear tab at the bottom portion of the wrapper. In this embodiment, the sealer table consists of spaced plates 154 and 156, the former being made wide and the latter comparatively narrow in order to form a longitudinal slot 158 near the end of the article to be wrapped. A revolving brush 160, provided to form the tear tab P, is carried by an intermit-

tently swinging arm 162 adjustably mounted on a cross shaft 164 of the machine. While in the present disclosure, the brush 160 is shown to revolve, it could also be made stationary because the swinging movement imparted to the brush carrying arm 162 is sufficient to bend the tear strip back to form a tear tab. The hub of arm 162 is provided with a shouldered bushing 166 on which turns a double pulley 168 receiving motion from a belt 170 driven from a suitable pulley (not shown) on the drive shaft of the machine. The other belt 172, of pulley 168, drives a pulley 174 which is clutched at 176 to the hub of brush 160. The brush and pulley combination is loosely mounted on a stud 178 supported in arm 162.

The intermittent oscillating motion imparted to arm 162 is accomplished by a shoe 180 mounted on each of the conveyor pusher arm shafts 182. As the article is being advanced rearwardly in the machine, shoe 180 trips an upstanding arm 184 placed in its path of travel, and depresses the same whereby an arm 186 also moves downwardly. Arms 184 and 186 are mounted on a stud 188 carried by a bracket 190 secured to the conveyor chain support bar 192 of the machine. The descent of arm 186 causes a link 194 connecting to a bell-crank lever 196 to swing the latter about its fulcrum 198. The vertical extending arm 200 of lever 196 is provided with a roller 202 adapted to engage in an open end slot 204 of a crank arm 206 keyed to shaft 164.

The motion thus imparted to shaft 164 causes it to swing arm 162 and its brush 160 into and out of engagement with the bottom of the passing articles. The positioning of arm 162 may be shifted to suit the location of the longitudinal slot in the sealer table, which is varied to accommodate different packages. To accomplish this object, the bushing 166 is provided with a keyway adapted to slide on the long key 208 in shaft 164. When correctly placed, so that the brush engages in the slot, a set screw 210 in the hub of arm 162 is tightened to secure the arm and bushing to the shaft.

When the shoe 180 engages arm 184, the latter is in its dotted position 183 holding the brush 160 in its dotted line position 159. In this manner, a portion of article A has passed said brush 50 when the same is in its starting position. The advance of shoe 180 moves the arm 184, carrying brush 160, to the position shown in full lines. The brush 160 is then ready to engage the bottom of the passing article as shown in full lines 55 in Fig. 10. The continued advance of shoe 180 depresses arm 184 to its down position 185, shown in dotted lines and causes arm 162 to continue advancing the brush 160 to the dotted line position.

60 The brush 160, in approaching position 161, engages the bottom of the wrapped article and brushes the slotted portion of the web downwardly and also wipes against the bottom of the article to form a tear tab P as shown in Fig. 10. While the drawings show the tear strip zone free from any heat-sealing element to facilitate forming the tear tab, the invention could also be practiced if a heat-sealing element were allowed to remain in the tear strip zone. The shoe 180 is 65 of sufficient length to hold arm 184 depressed until the article has passed the range of the swinging brush 160. In this manner, the possibility of disturbing the formed tab is overcome.

When the trailing edge of said shoe 180 passes 70 its engaging arm 184, a spring 212 returns the

arm 162 and arm 184 to their starting position. A stud 213 in bracket 190 is provided to act as a stop for arm 184. An arm 214, keyed on shaft 164 at its upper end supports a stud 216 which is provided to carry one end of spring 212. The other end of spring 212 is connected to a spring post 218 fastened in table 154.

A series of bottom sealer fingers 138 are incorporated and arranged as shown in Fig. 9 in such a manner that member 142 spaces the sealer fingers from the tear strip zone to avoid heat-sealing the tear strip.

The invention above described may be varied in constructions within the scope of the claims, for the particular device selected to illustrate the invention is but one of many possible embodiments of the same. The invention, therefore, is not to be restricted to the precise details of the structure shown and described.

What we claim is:

1. In a wrapping machine for applying a wrapper and tear strip about an article to be wrapped, a runway, mechanism for forwarding articles to be wrapped along said runway, mechanism for applying the wrapper and tear strip about articles being forwarded along said runway, heat-sealing means positioned in said runway adapted and arranged to heat-seal the overlapped portions of the wrapper and tear strip, a rotary brush positioned in said runway adapted and arranged to engage the end of the tear strip and brush it away from the wrapped article to form a tear tab.

2. A machine for wrapping articles such as bread, comprising, a wrapper feeding mechanism, a tear strip feeding mechanism, a means for joining the tear strip to the wrapper, a wrapper applying station, means for forwarding an article to be wrapped to said station, mechanism for applying the wrapper to the article to be wrapped, means for advancing said article from said station to a heat-sealing unit, said heat-sealing unit being adapted and arranged to remain out of contact with the portion of the wrapper carrying said tear strip, and means for pushing a portion of said wrapper and tear strip away from the wrapped article to form a readily accessible tear tab for gripping.

3. A wrapping machine comprising, a support for a roll of wrapping material, a support for a roll of tear strip material, mechanism for drawing off simultaneously wrapper material and tear strip material from both of said rolls, mechanism for joining the tear strip to said wrapper material, a wrapper applying station, means for pulling off a sufficient quantity of wrapper material and tear strip material from said rollers, a cutter for severing the wrapper and tear strip material removed from said rolls of wrapper and tear strip material, said cutter carrying means for forming slits in the wrapper on either side of said tear strip adjoining the point of severance of said wrapper and tear strip, means for applying the wrapper and tear strip about the article wrapped, means for heat-sealing the open seams of said wrapped article, means for forwarding said wrapped article along a runway, and a tab forming mechanism interposed in said runway for engaging said tear strip and slit wrapper to form a projecting readily accessible tear tab.

4. In a machine for wrapping articles such as bread, mechanism for applying a wrapper and tear strip about an article to be wrapped, mechanism for cutting a tear tab, mechanism for

forwarding said wrapped articles with a cut tear tab along a predetermined path having an elongated opening formed therein, and a moving member for engaging said cut tear tab to bend it way from the package.

5. In a wrapping machine having a support for holding a supply of wrapping material, a support for holding a supply of tear strip material, feeding means for feeding wrapping material and tear strip material together simultaneously to a wrapping station, means for applying the wrapper and tear strip about the article to be wrapped, a wrapper cutter for severing the wrapper after a sufficient amount of wrapping and tear strip material has been removed from the source of supply to apply about the article to be wrapped, a tear strip cutter connected to said wrapper cutter for severing the tear strip and wrapper portion attached thereto to form a tab, forwarding means for forwarding the wrapped articles along a runway having a longitudinal opening formed in the lower bed thereof, and a traveling member adapted and arranged to engage and bend the severed tear strip tab to cause it to project from the wrapped article.

6. In a wrapping machine of the type used for wrapping bread loaves, a support for holding a supply of wrapper material, a support for holding a supply of tear strip material, a guide arrangement for feeding said wrapper material and tear strip material together to a wrapper applying station, a heat-sealing element for causing the tear strip material to adhere to the wrapper material, means for forwarding an article to be wrapped to the wrapper applying station and for removing a sufficient amount of wrapper and tear strip material from the source of supply, means for applying said wrapper and tear strip material about said article to be wrapped, cutting means for severing the wrapper and tear strip material in such a way as to form a tab, means for forwarding said wrapped articles past sealing mechanism, said sealing mechanism being constructed and arranged to remain free from engagement with that portion of the wrapper to which the tear strip adheres, and means for engaging the tear strip tab and turning it back to project from the wrapped article to permit it to be readily gripped.

7. In a wrapping machine of the type used for wrapping bread loaves, a support for holding a supply of wrapper material, a support for holding a supply of tear strip material, a guide arrangement for feeding said wrapper material and tear strip material together to a wrapper applying station, a heat-sealing element for causing the tear strip material to adhere to the wrapper material, means for forwarding an article to be wrapped to the wrapper applying station and for removing a sufficient amount of wrapper and tear strip material from the source of supply, means for applying said wrapper and tear strip material about said article to be wrapped, cutting means for severing the wrapper and tear strip material in such a way as to form a tab, means for forwarding said wrapped articles past sealing mechanism, said sealing mechanism being constructed and arranged to remain free from engagement with that portion of the wrapper to which the tear strip adheres, a traveling brush, a support for said traveling brush, and actuating means for moving said brush in and out of engagement with the wrapped article to turn back and form a projecting tear tab.

8. In a wrapping machine of the type used for

wrapping bread loaves, a support for holding a supply of wrapper material, a support for holding a supply of tear strip material, a guide arrangement for feeding said wrapper material and tear strip material together to a wrapper applying station, a heat-sealing element for causing the tear strip material to adhere to the wrapper material, means for forwarding an article to be wrapped to the wrapper applying station and for removing a sufficient amount of wrapper and tear strip material from the source of supply, means for applying said wrapper and tear strip material about said article to be wrapped, cutting means for severing the wrapper and tear strip material in such a way as to form a tab, means for forwarding said wrapped articles past sealing mechanism, said sealing mechanism being constructed and arranged to remain free from engagement with that portion of the wrapper to which the tear strip adheres, and a brush mechanism for causing said brush to travel over a predetermined path to bring the brush into engagement with the bottom portion of the wrapped article to turn back the tear tab, said means being adapted and arranged to bring said brush in and out of engagement with the wrapped article.

9. A machine for wrapping articles such as bread, comprising, a source of supply of wrapper material and tear strip material, a wrapper applying station, means for feeding wrapper and tear strip material from said source of supply to said wrapper applying station, means for applying said wrapper and tear strip material about the article to be wrapped at said wrapper applying station, a cutter for severing the wrapper and tear strip material, a runway having a longitudinal opening therein under the portion of the wrapped article having the tear strip, a traveling arm adjoining said longitudinal opening, a brush mounted on said arm, and means for actuating said arm and brush to cause a tear tab to be formed on the article as it is forwarded along said runway.

10. A method of forming tear tabs on wrapped articles such as bread consisting of, feeding wrapper and tear strip material to a wrapper applying station, wrapping said wrapper and tear strip material about the article to be wrapped, cutting said wrapper and tear strip material in such a way as to form a tear tab, heat-sealing the overlapped portions of the wrapper, and bending the tear tab in a direction which causes it to project from the wrapped article.

11. The method of forming tear tabs on wrapped articles such as bread consisting of, removing wrapper material from a source of supply, removing tear strip material from a source of supply, joining said wrapper and tear strip material together, forwarding said joined wrapper and tear strip material to a wrapper applying station, wrapping said wrapper and tear strip material over an article to be wrapped, slitting a portion of the wrapper on either side of said tear strip, severing said wrapper and tear strip transversely across said slits, and then bending said slit portion outwardly from the package to form a tear tab.

12. A bread wrapping machine comprising, a runway, a wrapper applying station, means for forwarding articles to be wrapped along said runway, a source of supply of continuous wrapper

material, means for drawing off wrapper material from said continuous source of supply intermittently, means for applying said wrapper material about an article to be wrapped, a cutter for severing said wrapper from said continuous supply of wrapper material, slitting knives for inserting spaced slits in said wrapper material at a portion adjoining the severed end of the wrapper applied about said article, means for forwarding 10 said article along said runway, and means for turning back said slit portion to form a tear tab.

13. A bread wrapping machine comprising, a runway having an elongated opening running along a portion of the length of said runway, a 15 wrapper applying station, a source of supply of continuous wrapper material, a source of supply of continuous tear strip material, means for drawing off wrapper material and tear strip material simultaneously from said source of supply, means for joining said tear strip material to said wrapper material, mechanism operating to apply said wrapper about an article at a wrapper applying station, a cutter for severing said wrapper and tear strip material after an article 20 has been wrapped, slitting knives mounted on said cutter for slitting the wrapper on either side of the portion bearing said tear strip material, mechanism for folding the cut wrapper about the article to be wrapped, means for forwarding said wrapped articles along said runway so that the portion of the wrapper having the tear strip affixed thereto is over the open elongated portion of said runway, heat-sealing means positioned in said runway for sealing the portions of the wrapper 25 on either side of said tear strip portion, and a traveling brush positioned for travel in said runway for engaging the end of the wrapper bearing said tear strip portion to push the tear tab in a direction away from the package.

14. A bread wrapping machine comprising, a runway, a wrapper applying station, a source of supply of continuous wrapper material, a source of supply of continuous tear strip material, means for drawing material from said source of supply 30 of continuous wrapper material and from said source of supply of continuous tear strip material and feeding the same longitudinally in the same direction toward said wrapper applying station, mechanism for applying said wrapper and tear strip material about the article wrapped, cutting means for intermittently severing said wrapper and tear strip material, said cutting means being constructed and arranged to form 35 a tear tab when severing said wrapper and tear strip material, and means for engaging said tear tab to push it away from the package to facilitate the gripping of the same.

THORMOD JENSEN.
FREDERICK A. DRURY.
